UNITED STATES PATENT OFFICE.

DAYTON A. DUSENBERY, OF IONIA, KANSAS.

CART.

1,293,058.

Specification of Letters Patent.

Patented Feb. 4, 1919.

Application filed December 31, 1917. Serial No. 209,669.

To all whom it may concern:

Be it known that I, DAYTON A. DUSENBERY, a citizen of the United States, residing at Ionia, in the county of Jewell and State of Kansas, have invented certain new and useful Improvements in Carts, of which the following is a specification.

This invention relates to improvements in vehicles, more particularly to hand carts, and has for one of its objects to form the major portion of the body from a single section of material or plank whereby the sides, handles and the cleats for supporting the ends of the body, may be cut therefrom without appreciable waste of material.

Another object of the invention is to provide a device of this character having a stay member extending between the handles and supporting and reinforcing the latter.

With these and other objects in view, the invention consists in certain novel features of construction, as hereinafter shown and described and then specifically pointed out in the claims; and in the drawings illustrative of the preferred embodiment of the invention—

Figure 1 is a view of the plank or board from which the sides, handles and cleats of the body portion of the vehicle are constructed.

Fig. 2 is an elevation of the completed cart from the rear.

Fig. 3 is a view of the completed cart from the front.

Fig. 4 is an enlarged sectional detail illustrating the manner of constructing and connecting the stay member to the handles of the cart.

Fig. 5 is a side elevation of the completed cart.

Fig. 6 is a plan view of the completed cart.

Figs. 7 and 8 are enlarged sectional details of one of the coupling devices whereby the bottom is coupled to the side members of the cart.

The body portion of the improved device including the sides, handles, and the cleats whereby the ends of the body are retained in position, are formed from a single section or board without appreciable waste of material, as illustrated in Fig. 1. To construct the sides, handles, and cleats, the section of material is divided intermediate its ends, first by sawing or otherwise forming clefts 10 at right angles to the opposite side edges

of the body and in spaced relation, and then connecting these clefts by a plurality of other clefts indicated at 11. By this means the side portions of the body of the 60 cart, represented at 12—13, are produced with projections 14—15 extending respectively from the inner ends of the side portions and constituting the handles of the body. The clefts 11 produce a plurality of 65 strips which when severed transversely intermediate their ends form the cleats, indicated at 16, whereby the ends 17—18 of the body are supported in position relative to the sides. In laying out the lines for the 70 production of the clefts the distance between the shorter clefts 10 is a trifle greater than twice the height or vertical distance of the sides 12—13 so that after the strips are produced they may be cut into the required lengths.

After the sides have been produced by the saw cuts above noted the smaller reduced ends of the members 14—15 are rounded to form hand grips as indicated at 19—20. The 80 bottom member of the body is represented at 21 and bearing beneath the bottom 21 near its ends are transverse cleats 22—23. Formed in the inner faces of the sides 12—13 beneath the cleats 16 are cavities or 85 seats, indicated at 35, to receive eye bolts 36 which are thus embedded in the cavities and covered by the cleats 16. Clamp bolts 37 extend through the sides 12—13, the cleats 16 and the eyes of the bolts 36, as shown. 90

The bolts 36 extend downwardly through the bottom 21 and the transverse cleats 22 and are threaded to receive binding nuts 38. By this means the sides and bottom are firmly coupled together, and readily separable, 95 when required. Transverse tie rods 24—25 extend through the sides 12—13 near their upper edges, and likewise through the cleats 16 externally of the end member 18, and internally of the end member 17. By this 100 arrangement the end member 17 may be removed to discharge the load and leave the tie rod 25 intact to support the sides 12—13 and prevent outward displacement under the lateral strain of the load.

Extending between the handle members 14—15 near the grip portions 19—20 is a tubular stay member 26. Extending through the handles 14—15 and into the stay member 26 are rods 27—28, the rods having 110 eyes at their inner ends to receive holding pins 29—30 which extend through the tubu-

lar member 26. At their outer ends the bolts 27-28 are provided with clamp nuts 31-32. By this means it will be obvious that the handle members and the tie member 5 will be firmly clamped in position and reinforce the handle members. The tubular member likewise serves as a transverse supplemental handle, to assist in operating the vehicle. By this arrangement it will be 10 obvious that a very strong, durable and simply constructed cart member is produced without appreciable waste of material. It will be noted by reference to Fig. 1 that practically the only waste of material occurs 15 at the terminals of the cleft 11 as indicated at 33-34.

Having thus described the invention what is claimed as new is:

1. A vehicle body including parallel sides 20 in spaced relation and each having a handle formed integral therewith and extending longitudinally from one end thereof, a tubular stay member extending between the outer ends of said handles, holding devices extending through the handles and into the 25

tubular stay member and having eyes at their inner ends, holding pins engaging through said stay member and through said eyes, and means for exerting a longitudinal pull on said holding devices. 30

2. A vehicle body including a bottom, spaced sides supported on the bottom and having their inner faces cut away to form vertical seats, transverse cleats disposed beneath the bottom, vertical guide cleats attached to the inner faces of said sides and forming closures for the adjacent seats, end members supported by said cleats, bolts housed within said seats and having their upper ends provided with eyes and their lower ends extended through said bottom and transverse cleats, clamp bolts extending through said sides, guide cleats and eyes of the bolts, and clamp nuts engaging said eye bolts and bearing against the transverse 45 cleats for exerting a longitudinal pull on said eye bolts. 35

In testimony whereof I affix my signature.

DAYTON A. DUSENBERY.
